UNITED STATES PATENT OFFICE.

ISAAC ROBERT MATTHEWS, OF BARNESVILLE, GEORGIA.

DOOR-CHECK.

No. 872,529.

Specification of Letters Patent.

Patented Dec. 3, 1907.

Application filed May 14, 1907. Serial No. 873,648.

To all whom it may concern:

Be it known that I, ISAAC R. MATTHEWS, a citizen of the United States, residing at Barnesville, in the county of Pike and State 5 of Georgia, have invented certain new and useful Improvements in Door-Checks, of which the following is a specification.

This invention relates to a door check or retainer.

10 One object of the invention is to provide a device of the nature stated embodying such characteristics that it may engage the door automatically and retain the same in open position until manually operated to release 15 the door.

Another object of the invention resides in the provision of a door check or retainer constructed and arranged for disposition in the path of movement of the door so that when 20 the door is opened it may engage the check or retainer and be automatically held in its open position with a minimum of frictional engagement between the door and check or retainer.

25 With the above and other objects in view, the present invention consists in the combination and arrangement of parts hereinafter more fully described, illustrated in the accompanying drawings, and particularly 30 pointed out in the appended claims, it being understood that changes may be made in the form, size, proportion, and minor details without departing from the spirit or sacrificing any of the advantages thereof.

35 In the drawings:—Figure 1 is a fragmentary perspective view of the door frame and door in its open position and in engagement with my improved door check or retainer. Figs. 2, 3 and 4 are diagrammatic plan views 40 indicating the manner of operation of the invention in several of the positions assumed by the device when the door is moved into engagement with the same. Fig. 5 is a sectional view on the line *a—a* of Fig. 1.

45 My improved door check or retainer embodies such characteristics that there is very little friction between the same and the door when they are engaged one by the other, and the door is designed to move the check or 50 retainer into coöperative relation therewith

without the instrumentality of one or more projections upon the door.

The device is of such character that it may be used with any door without separate or intermediate connections. 55

Before entering into detail it might be stated that the invention consists essentially of a curved body member pivoted intermediate its ends and provided at each end with a roller so mounted that it may rotate upon 60 its pivot simultaneously with a movement of the body of the check or retainer, the rotation of the rollers and simultaneous movement of the body being accomplished by the door, and the door being held securely in its 65 open position until the check is manually operated to permit closing of the door. To permit closing of the door the check or retainer may be engaged by one's foot to be shifted out of its checking or retaining position. 70

In the accompanying drawings, the reference character 1 indicates a door and 2 the body portion of my invention, the body portion being preferably curved, arcuate in shape or as shown, and pivotally connected to the 75 floor intermediate its ends through the instrumentality of a screw or other suitable pivot connection 3. A perforation is formed in each end of the curved body 2 for the reception of the reduced end 4 of the posts 5. 80 These posts 5 are designed to form bearings for the support of the rubber or other rollers 6, which may be slipped upon the posts 5 and readily removed therefrom.

In the use of my invention, it is placed at 85 such an angle as to permit the door in its opening movement to pass the first roller 6 and engage the opposite roller, the striking of the opposite roller by the door causing the first knob to be thrown behind the door, 90 leaving the free side edge of the door between the rollers until released, whereby the door cannot accidentally close.

While the rollers 6 fit comparatively tight upon their bearings, they do have movement thereupon, so that when the door strikes the rollers they may move simultaneously with a bodily movement of the body thereof upon their pivot. By reason of the simultaneous rotation of the engaged rollers 100

with the body of the device, friction is reduced to a minimum, and in the use of rubber or other soft rollers marring of the door is obviated.

5 Having thus described my invention, what I claim and desire to secure by Letters Patent is:—

A door check or retaining device comprising a flat arcuate shaped body provided with 10 a perforation intermediate its ends, and a

roller mounted at each end of the body, the body upon each side of said perforation being the same length.

In testimony whereof I affix my signature, in presence of two witnesses.

ISAAC ROBERT MATTHEWS.
